US0D1028296S

(12) **United States Design Patent** (10) **Patent No.:** **US D1,028,296 S**
(45) **Date of Patent:** **** May 21, 2024**

(54) **LIGHTING ADAPTER**

(71) Applicant: **BELLSON ELECTRIC PTY LTD**,
Caringbah (AU)

(72) Inventor: **David John Sanson**, Taren Point (AU)

(73) Assignee: **BELLSON ELECTRIC PTY LTD**
(AU)

(**) Term: **15 Years**

(21) Appl. No.: **29/825,645**

(22) Filed: **Feb. 3, 2022**

Related U.S. Application Data

(63) Continuation of application No. 17/562,343, filed on Dec. 27, 2021, now Pat. No. 11,635,192.

(51) **LOC (14) Cl.** **26-06**

(52) **U.S. Cl.**

(57) **CLAIM**

I claim the ornamental design for a lighting adapter, as shown and described.

DESCRIPTION

FIG. 1 is a front, right side, isometric view of the lighting adapter;

FIG. 2 is a front, left side, isometric view thereof;

FIG. 3 is a rear, right side, isometric view thereof;

FIG. 4 is a rear, left side, isometric view thereof;

FIG. 5 is a side view thereof;

FIG. 6 is a front view thereof;

FIG. 7 is a rear view thereof; and,

FIG. 8 is a side view of the lighting adapter within its environment.

The broken lines shown in FIG. 8 depict environmental structure which forms no part of the claimed design.

1 Claim, 8 Drawing Sheets
